HENRI BESSONNET-FAVRE, OF CHATELLERAULT, FRANCE, ASSIGNOR TO SOCIÉTÉ ANONYME DES ÉLÉVATEURS DE LIQUIDES "CHAÎNE-HÉLICE" BESSONNET-FAVRE, OF CHATELLERAULT, FRANCE.

LIFTING-CHAIN WITH MULTIPLE CONCENTRIC SPIRALS FOR RAISING LIQUIDS.

988,301.

Specification of Letters Patent.

Patented Apr. 4, 1911.

Application filed June 13, 1910. Serial No. 566,637.

To all whom it may concern:

Be it known that I, HENRI BESSONNET-FAVRE, a citizen of the Republic of France, residing at Châtellerault, Vienne, France, 5 have invented new and useful Improvements in Lifting-Chains with Multiple Concentric Spirals for Raising Liquids, which improvements are fully set forth in the following specification.

10 This invention relates to devices for raising water or other liquids, and more particularly to such devices which comprise essentially a traveling chain or cable, and which are known as chain pumps.

15 The object of the invention is to provide an improved construction of chain or cable which, while compact and simple in construction, will transport relatively large quantities of liquid, and which will be extremely durable and little liable to get out 20 of order.

To this end, I have devised a cable which depends for its carrying power upon capillary attraction or the natural adhesion of 25 liquids.

My improved cable is constructed so as to contain a large number of intercommunicating spaces or interstices, in which spaces, by virtue of its natural adhesive tendency, 30 the liquid is held in suspension.

In order that my invention may be readily understood, reference is had to the accompanying drawings, forming a part of this specification, and in which,

35 Figure 1 is a side elevation of a pump showing my improved conveyer in use, parts being in section; Fig. 2 is a fragmentary elevation, on an enlarged scale, showing the construction of the conveyer, and, Fig. 3 is 40 a similar view, parts of the conveyer being shown in section.

Referring to Figs. 2 and 3, my improved conveyer consists essentially of a plurality of concentrically arranged open work tubular elements, here illustrated as helical springs. Two of such springs, designated 45 B and C, respectively, are shown, the inner one B, being shown as formed of smaller wire than the outer one, and having its 50 convolutions closer together. To form a support for these springs or coils, I provide a centrally arranged chain or cable A which, as shown, consists of links of 8-shape, extending throughout the length of the con-

veyer; the ends of this chain may be joined 55 together as by means of a lap link E and a swivel link D, thus forming an endless cable. In order to prevent undue stretching of the wire coils B and C under the weight of the water, as well as to hold these coils properly 60 spaced in the position illustrated in the drawing, they are secured at intervals to the chain A by passing one or more times through a link of the chain, as illustrated at B and C in Fig. 2.

65 The complete endless conveyer or cable, constructed as described, is adapted to be mounted upon a grooved pulley P, over a well, so that the lower portion of the conveyer is immersed in the water, as shown in 70 Fig. 1. A weighted pulley P' may be hung in the bottom of the cable so as to preserve a proper tension, if desired.

The size of the wire of the several coils, the distances apart of these coils, and of the 75 consecutive turns of each coil, is governed by the particular use to which the conveyer is to be put. The viscosity of the liquid to be pumped and the speed at which the cable is to be run, are factors in determining the 80 relative spacing and size of the coils, as it is obvious that, where the liquid is viscous, the interstices may be larger than in the case of a very limpid liquid. Also, it is 85 obvious that any number of coils desired may be employed, depending upon the capacity required, the greater the number of coils, the greater the amount of liquid lifted.

90 Whatever the specific arrangement adopted, it will be observed that between the concentric tubular coils and between the innermost coil and the chain, annular spaces are formed, and that these spaces are rendered intercommunicating by virtue of the spaces between the adjacent turns of each coil. 95 When the conveyer is submerged, the liquid fills all of these spaces and interstices, and as the conveyer travels upward the liquid is held in suspension in such interstices, the spacing of the coils being so designed that, 100 for the particular liquid being conveyed, capillary or natural adhesion is sufficient to cause the liquid to remain in the conveyer.

105 When the liquid laden cable reaches the pulley P and passes over the same, the liquid will be thrown from the cable by centrifugal force in the direction of a tangent to the

pulley P, and will strike the shield or cover placed over such pulley, and be deflected into a discharge spout.

To produce the most efficient operation 5 of the device it should be run at a speed that will insure the total disengagement of the liquid from the cable, in the manner just described.

It will thus be seen that I have provided 10 a simple and efficient pump or liquid conveyer which may be formed wholly of metal or other durable or non-absorbent material, and it is thought that the advantages of my improved construction will be evident to 15 those skilled in such matters.

What I claim is:—

1. In a chain pump, a conveyer comprising a plurality of openwork tubular elements concentrically arranged and separated 20 so as to provide between themselves an annular space adapted to contain the liquid to be conveyed.

2. In a chain pump, a conveyer comprising a plurality of helical springs concentrically arranged and separated so as to provide 25 between themselves an annular space adapted to contain the liquid to be conveyed.

3. In a chain pump, a conveyer comprising

ing a plurality of helical springs concentrically arranged and separated so as to provide between themselves an annular space adapted to contain the liquid to be conveyed, and a centrally disposed inextensible flexible member to prevent undue stretching 35 of said springs.

4. In a chain pump, a conveyer comprising an endless cable formed of impervious non-absorbent material, said cable having within itself intercommunicating spaces or 40 interstices adapted to hold in suspension therein the liquid to be conveyed.

5. In a chain pump, a conveyer comprising an endless cable made up of a plurality of structural elements formed of non-absorbent material, said elements being so arranged as to provide between themselves intercommunicating spaces of a size adapted 45 to hold in suspension, by virtue of natural adhesion, the liquid to be conveyed.

In testimony whereof I have signed this specification in the presence of two subscribing witnesses.

HENRI BESSONNET-FAVRE.
